CLAIM

The ornamental design for a toothbrush with handle, as shown and described.

DESCRIPTION

FIG. 1 is a front view of a first embodiment of a toothbrush showing my new design;

FIG. 2 is a left side elevational view thereof;

FIG. 3 is a top view thereof;

FIG. 4 is a bottom elevational view thereof; and

FIG. 5 is a rear elevational view thereof.

The right side elevational view would be a mirror image of the left side elevational view in FIG. 2.
